UNITED STATES PATENT OFFICE.

CHARLES E. FISHER AND PERCY W. AULAR, OF TITUSVILLE, PENNSYLVANIA, ASSIGNEES TO THE TITUSVILLE IRON WORKS COMPANY, OF TITUSVILLE, PENNSYLVANIA, A CORPORATION OF OHIO.

DRILL-STEM BUSHING FOR WELL-BORING APPARATUS.

Application filed October 26, 1923. Serial No. 671,051.

To all whom it may concern:

Be it known that we, CHARLES E. FISHER and PERCY W. AULAR, citizens of the United States, residing at Titusville, in the county 5 of Crawford and State of Pennsylvania, have invented new and useful Improvements in Drill-Stem Bushings for Well-Boring Apparatus, of which the following is a specification.

10 This invention relates generally to a well-boring apparatus but more particularly to the sectional drive-bushing of the drill stem. Its chief object is to provide the drive bushing with simple and reliable means for 15 holding its sections together as a unit, to prevent their falling apart during the operation of withdrawing the bushing from the rotary table.

Another object of the invention is to construct the bushing sections so that they are 20 identical in form and shape and readily interchangeable, rendering it unnecessary to make separate male and female sections and correspondingly reducing the cost of manufacture.

25 A further object is to provide the sections of the bushing with complementary interlocking means which permit the sections to be assembled and separated by a relatively horizontal movement.

30 A still further object of the invention is to provide the bushing-sections with novel means for reliably locking them against vertical movement relative to each other.

35 With the above and other objects in view, the invention consists in the novel features of construction and arrangement of parts hereinafter described, and particularly pointed out in the appended claims.

40 In the accompanying drawings: Figure 1 is a vertical section of the rotary table of a well-boring apparatus, showing our improved drive bushing in position. Figure 2 is an enlarged top plan view, partly in section, of the bushing. Figure 3 is a vertical section in the plane of line 3—3, Fig. 2. Figure 4 is a perspective view of one of the bushing sections. Figure 5 is a similar view 45 of the locking bolt associated with each bushing-section.

50 Similar characters of reference indicate corresponding parts throughout the several views.

Referring now to Fig. 1 of the drawings,

the numeral 10 indicates the rotary table of 55 the well-boring machine which is rotated by the customary pinion 11. This table is provided with a square center opening 12 in which is seated the usual split table-bushing 13 having a bore whose upper portion 14 is square while its lower portion 15 is conical. Seated in the bore of the table-bushing is the improved drive bushing 16 which is of 60 the same shape as that of said bore and which is provided with a square center hole 17 with which the drill pipe engages, whereby by the rotary motion of the table is imparted thereto for boring or drilling.

The improved drive bushing preferably 65 consists of two complementary half-sections 18, 18 which are identical in size and form, both possessing the same features of construction and including duplex reciprocal interlocking elements. Each section is provided in its inner or meeting face with a 70 central longitudinal groove 19 which constitutes half of the bushing hole 17. Formed integral with each section and located adjacent one of the longitudinal edges of its central groove is a male interlocking 75 element preferably in the form of a substantially half dove-tail tongue 20, while arranged along its opposite edge is a similarly shaped female interlocking element in the 80 form of a groove 21. The inner face 22 of 85 the tongue 20, as shown in Figs. 2 and 4 is straight, so as to conform to and form a part of the corresponding side wall of the square bushing hole 17, and that face of 90 each tongue and groove parallel with the main or meeting joint of the sections extends to one of the vertical or upright edges 95 of the corresponding section. When the half sections are placed together in the position shown in Fig. 2, the companion tongues 95 and grooves interlock with each other to prevent horizontal displacement of said sections. By this construction, the sections can 100 be conveniently assembled and separated by a movement in a horizontal plane and in a direction diagonally of the meeting faces of the sections.

In order to hold the sections of the drive bushing together as a unit and prevent them from falling apart in withdrawing them 105 from the rotary table, means are provided for locking the sections against vertical displacement on each other. For this purpose,

each section is preferably provided with a horizontally-sliding locking bolt 23 guided in openings 24 located adjacent the upper end of the section and at one side of the 5 longitudinal groove 19. On the opposite side of the latter, each section is provided with a horizontal opening 25 adapted to receive the locking-bolt of the companion section. Said locking-bolt is provided with a 10 suitable handle 26 and the bolt is reliably held in its retracted and projected positions by the handle thereof engaging in one or the other of a pair of notches 27 formed in the corresponding upper end of each section.

15 In shifting the bolt from one position to the other, it is only necessary to grasp its handle, rock the same in the proper direction to withdraw it from the respective notch 26, shift the bolt in the direction desired and 20 then turn the handle into engagement with the other notch.

The locking bolts 23, while preventing vertical displacement of the bushing sections on each other, also hold them against 25 pulling apart laterally relatively to each other and in a direction parallel to or at an angle to the meeting faces of the sections.

If desired, the bushing sections may be 30 provided with the customary loops 28 to which handles may be attached for conveniently handling these parts.

Aside from the advantages of simplicity of construction and cheapness of manufacture, this improved drill stem drive bushing can be quickly assembled and dismembered and its sections can be reliably locked together to prevent their falling apart during the withdrawal thereof from the rotary 35 table. Furthermore, by constructing the sections identical in form with reciprocal tongues and grooves or equivalent interlocking elements, the sections are interchangeable and it is only necessary to manufacture 40 and carry in stock one style of section, thus avoiding the use of the separate male and 45 female sections heretofore required.

We claim as our invention:

1. A drill stem bushing of the character 50 described, comprising complementary sections, each section having on its inner face a tongue and a groove arranged to interlock with the corresponding elements of the other section, one of the side walls of 55 each tongue being exposed and forming a continuation of the corresponding side wall of the respective section, the groove of the latter being open at the joint face thereof and at the side facing the opposite side wall of said section.

2. A drill stem bushing of the character 60 described, comprising complementary sections, each section having on its inner face

a tongue and a groove, arranged to interlock with the corresponding elements of the 65 other section, that face of each tongue and groove parallel with the main joint of the sections extending to the upright edge of the corresponding section.

3. A drill stem bushing of the character 70 described, comprising a pair of interchangeable sections, each section having reciprocal interlocking means, said means being constructed to lock the sections against lateral separation in a plane at right angles to 75 their meeting faces, while permitting lateral separation thereof in substantially the plane of to said meeting faces.

4. A drill stem bushing of the character 80 described, comprising a pair of interchangeable sections, each section having reciprocal interlocking means, said means being constructed to lock the sections against lateral separation in a plane at right angles 85 to their meeting faces while permitting lateral separation thereof in the plane of such meeting faces, and separate means for locking said sections against relative longitudinal displacement.

5. A drill stem bushing of the character 90 described, comprising a pair of interchangeable sections, each section having male and female elements arranged to interlock with the corresponding elements of the other section for holding the sections against pulling apart laterally, each section also having a movable locking member arranged to engage the other section to prevent longitudinal displacement of the sections relative to each other. 95

6. A drill stem of the character described, 100 comprising a pair of sections provided in their meeting faces with upright dove-tail tongues and grooves and at opposite sides with transverse openings, and a locking bolt arranged in one of the openings of each section for engagement with the opposing opening of the companion section. 105

7. A drill stem of the character described, 110 comprising a pair of sections provided in their meeting faces with upright dove-tail tongues and grooves and at opposite sides with transverse openings, and a sliding locking bolt having a handle and arranged 115 in one of the openings of each section for engagement with the opposing opening of the companion section, each of said sections having retaining notches for receiving said bolt-handle. 120

8. A drill stem bushing-section having a tongue and groove on its inner face, a locking bolt mounted in one side of the section, the section having a bolt-receiving opening at its opposite side. 125
